UNITED STATES PATENT OFFICE.

JULIUS HAMMESFAHR, OF NEWARK, NEW JERSEY, ASSIGNOR TO THE R. NEUMANN HARDWARE CO., A CORPORATION OF NEW JERSEY.

BAG-FASTENER.

1,132,932.

Specification of Letters Patent. Patented Mar. 23, 1915.

Application filed January 7, 1915. Serial No. 898.

To all whom it may concern:

Be it known that I, JULIUS HAMMESFAHR, a citizen of the United States, residing at Newark, in the county of Essex and State of New Jersey, have invented certain new and useful Improvements in Bag-Fasteners; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 The present invention has reference, generally, to improvements in bag-fasteners or catches which are ordinarily employed with the hinged frame-sections of bags, suitcases, and the like; and, the invention relates, 20 more particularly, to that class of bag-frame fasteners comprising a main-shell, a slidable bolt element, and releasable means for locking said bolt element in its engaged or holding relation to the catch elements of 25 the opposite frame-section.

The present invention has for its principal object to provide a bag-frame fastener comprising a chambered shell or casing and a slidable bolt-carrying operating plate mov- 30 ably related to said chambered shell or casing, a spring locking means for retaining the bolt, carried by said bolt-carrying operating plate, in its engaged or locking relation to the catch elements of the opposite 35 frame-section, and means for automatically moving said bolt-carrying operating plate and its bolt to unlocked or disengaged relation to said catch elements of the opposite frame-section, when released from the re- 40 taining action of said spring locking means.

The invention has for its further object to provide a bag-frame fastener of the general character hereinafter more particularly set forth, with a view of providing a bag- 45 frame fastener of neat and simple appearance, and one which may be quickly and easily brought into its locking or unlocked relation by exceedingly simple manipulations.

50 Other objects of the present invention not at this time more particularly enumerated will be clearly evident from the following detailed description of the invention.

With the various objects of the invention 55 in view, the said invention consists, prima-

rily, in the novel bag-frame fastener herein-after set forth; and, furthermore, the invention consists in such novel arrangements and combinations of parts, as well as in the details of the construction of the same, all 60 of which will be more fully described in the following specification, and then finally embodied in the clauses of the claims which are appended to and which form an essential part of this specification. 65

The invention is clearly illustrated in the accompanying drawings, in which:

Figure 1 is a plan view of one end of a bag-frame in closed position, and equipped with the novel bag-frame fastener made according to and embodying the principles of my present invention. Fig. 2 is a side elevation of the same. Fig. 3 is a detail vertical longitudinal section of the same, drawn on an enlarged scale, and illustrating the 75 novel bag-frame fastener in its locking or fastening position. Fig. 4 is a detail view similar to that shown in Fig. 3, but illustrating the novel bag-frame fastener in its unlocked or unfastened position. Fig. 5 is a horizon- 80 tal section of the novel bag-frame fastener, taken on line 5—5 in said Fig. 3, looking downward. Fig. 6 is a bottom view of said novel bag-frame fastener removed from its frame-section, and the same is shown with 85 the spring locking means and bottom-plate thereof removed, to more clearly illustrate the connection of the actuating spring of the sliding bolt element.

Similar characters of reference are em- 90 ployed in the said above-described views to indicate corresponding parts.

Referring now to the said drawings, the reference character 1 indicates one frame-section of bag-frame, or the like, and the reference character 2 indicates the opposite frame-section. 95

The reference character 3 indicates the top-wall, 4 the longitudinally extending side-members or walls, and 5 the laterally extending end-members or walls of the main shell or casing of the bag-frame fastener, the same providing a suitably chambered body upon and in which the operative parts of the fastener mechanism are supported. 100

The reference character 6 indicates an exterior slidable bolt-carrying plate which is slidably supported upon the top-wall 3 of said chambered body. Connected with said bolt-carrying plate 6 is a downwardly and 110

vertically extending bolt-element 7, the same being secured to said bolt-carrying plate 6 by means of suitable rivet-portions 8, or any other equivalent or suitable fastening means. 5 The said top-wall 3 of said chambered body is provided with a suitably disposed longitudinally extending slot 9, through which said bolt-element 7 extends so as to pass downwardly through the interior of said 10 chambered body, said slot 9 being of sufficient length to permit the necessary longitudinal movement of said bolt-element relative to said chambered-body. In order to retain said bolt-carrying plate 6 and its bolt-element 7 in proper relation to said chambered body there is provided a keeper-plate 10 which registers against the inner or under side of said top-wall 3 of said chambered body, said keeper-plate 10 having a slot 15 through which said bolt-element extends for the purpose of assembling the said parts, and said bolt-element being further provided with retaining or stop-lugs 11 overlapping said keeper-plate and serving to retain the 20 same against removal from its proper associated relation to said bolt-element. The lower free end of said bolt-element provides a holding-portion 12 which may be moved into engagement with hook-like catch elements 13 which extend from and are secured to the frame-section 2, in the usual and well-known manner. Connected with said bolt-element 25 7 and spaced slightly away from said holding-portion 12 thereof is a catch-nosing 14, the purpose of which will presently appear. Inserted in the lower open portion of said chambered body is a bottom-plate 15, the same being provided with an elongated longitudinally extending slot 16 30 through which said holding-portion 12 of said bolt-element 7 projects.

The reference character 17 indicates a spring lock-plate, the same being bifurcated at one end to provide the arms 18 45 which straddle said holding-portion 12 of said bolt-element 7. Said arms 18 are secured by the rivets 19 or any other suitable fastening devices, to the said bottom plate 15, so as to anchor said spring lock-plate 17 50 in proper fixed location within said chambered body. Said spring lock-plate 17 inclines upwardly within said chambered body and extends beneath said catch-nosing 14 of said bolt-element, said spring-lock plate 17 55 being provided with a properly located receiving opening 20 into which said catch-nosing 14 is received or projects with locking effect when said bolt-element 7 is moved to register said catch-nosing 14 with said 60 receiving opening 20, thereby locking said bolt-element in an unmovable position until said spring lock-plate 17 is depressed to release said catch-nosing 14. Said catch-nosing 14 is further provided with a chamfered 65 or rounded edge portion 21 which serves to

automatically depress said spring lock-plate, when moving said bolt-element into position to register its catch-nosing 14 with the receiving-opening 20. The free end of said spring lock-plate 17 is provided with a 70 neck-piece or tongue 22 which passes through an opening 23 in an end-member or wall 5 of said chambered body, to exteriorly present said neck-piece or tongue without said chambered body. A suitable knob or 75 finger-piece 24 is secured to the exterior end of said neck-piece or tongue, and the same serves as a means for depressing said spring lock-plate to release the same from holding engagement with said catch-nosing of said 80 bolt-element.

Secured to the interior side of the opposite end-member or wall 5 of said chambered body is an anchor-plate 25 out of which is pressed, or with which is connected 85 in any other suitable manner, a hook-like member 26 which serves to engage and anchor one end of a pull-spring 27, the opposite end of which is secured operatively to said bolt-element 7 by engaging the same 90 with a similar hook-like member 28 pressed out of or otherwise connected with said keeper plate 10. Said bag-frame fastener thus constructed is secured to said frame-section 1 by means of fastening lugs or 95 prongs 29, which project from the chambered body and pass through openings in said frame section suitably located for that purpose, the lugs or prongs being then turned over against the frame-section to 100 prevent their withdrawal. Of course any other desirable means of securing the bag-frame fastener to the frame-section may be employed, without departing from the scope 105 of this invention. Said frame-section 1 is further provided with a slot 30 registered with the slot 16 of said bottom plate 15, through which the holding-portion 12 of the bolt-element projects so as to be capable 110 of being moved into and out of engagement with said catch-elements 13 of the opposite frame-section 2.

Referring now to Figs. 1 to 3 inclusive, the novel bag-frame fastener above described is shown operated to position the 115 holding-portion 12 of its bolt-element 7 in its fastening relation to the catch-elements 13. Said bolt-element is retained in such fastening relation by means of the spring lock-plate 17 the receiving opening 20 of which 120 embraces said catch-nosing 14 and prevents the sliding movement of said bolt-element whereby its holding portion is carried away from said catch-element 13. It will thus be 125 apparent that the bag-frame fastener is locked in fastening relation against accidental displacement from such relation, yet it is exceedingly easy to release the same from such fastening relation by simply pressing downwardly upon the finger-piece 130

24 whereby said spring lock-plate 17 is depressed so that its receiving opening 20 is carried away from said catch-nosing 14, thus releasing said bolt-element 7 to the pulling influence of said pull-spring 27, which thereupon automatically slides said bolt-element and bolt-carrying plate longitudinally thereby carrying said holding portion 12 away from its engagement with said catch-element 13, the parts then assuming the positions illustrated in Fig. 4 of the drawings. When it is desired to lock said fastener, the carrying-plate is pushed back to normal position, thereby reversing the sliding movement of said bolt-element and carrying its holding-portion 12 again into engagement with said catch-elements 13, at the same time the chamfered or rounded edge-portion 21 of said catch-nosing rides against said spring lock-plate 17 automatically depressing the same until the receiving opening 20 of the latter registers with said catch-nosing whereupon the spring lock-plate 17 resumes normal position with said catch-nosing projecting into said receiving opening 20, and the bolt-element 7 being thereby again locked against release until said spring lock-plate 17 is again depressed by the manipulation of its finger-piece.

Of course, I am fully aware that some changes may be made in the general arrangements and combinations of the several devices and parts, as well as in the details 35 of the construction of the said parts, without departing from the scope of the present invention as set forth in the foregoing specification and as defined in the claims which are appended to the said specification. 40 Hence, I do not limit myself to the exact arrangements and combinations of the several parts as described in the said specification, nor do I confine myself to the exact details of the construction of the said parts as 45 illustrated in the accompanying drawings.

I claim:—

1. A bag-frame fastener comprising a chambered shell, a bolt carrying plate slidably connected with said shell, a bolt element depending from said bolt carrying plate, a releasable locking means for retaining said bolt carrying plate and its bolt-element in fastening position, and an actuating spring for sliding said bolt carrying plate and its bolt-element out of fastening position.

2. A bag-frame fastener comprising a chambered shell slotted in its upper wall, a bolt-carrying plate mounted to slide on the exterior side of the upper wall of said shell, a bolt-element depending from said bolt carrying plate and extending downwardly through said shell, a keeper-plate connected with said bolt-element and slidably registered with the under surface of said upper

wall of said shell, a releasable locking means for retaining said bolt carrying plate and its bolt-element in fastening position, and an actuating spring for sliding said bolt-carrying plate and its bolt-element out of fastening position.

3. A bag-frame fastener comprising a chambered shell slotted in its upper wall, a bolt-carrying plate mounted to slide on the exterior side of the upper wall of said shell, a bolt-element depending from said bolt carrying plate and extending downwardly through said shell, a keeper-plate connected with said bolt-element and slidably registered with the under surface of said upper wall of said shell, a catch-nosing connected with said bolt element and disposed within said shell, and a depressible spring lock-plate arranged within said shell and provided with a receiving opening adapted to 80 embrace said catch-nosing.

4. A bag-frame fastener comprising a chambered shell slotted in its upper wall, a bolt-carrying plate mounted to slide on the exterior side of the upper wall of said shell, a bolt-element depending from said bolt carrying plate and extending downwardly through said shell, a keeper-plate connected with said bolt-element and slidably registered with the under surface of said upper wall of said shell, a catch-nosing connected with said bolt-element and disposed within said shell, a depressible spring lock-plate arranged within said shell and provided with a receiving opening adapted to 90 embrace said catch-nosing, and an actuating spring for sliding said bolt carrying plate and its bolt-element in one direction when said catch-nosing is released from said spring lock-plate.

5. A bag-frame fastener comprising a chambered shell slotted in its upper wall, a bolt-carrying plate mounted to slide on the exterior side of the upper wall of said shell, a bolt-element depending from said bolt carrying plate and extending downwardly through said shell, a keeper-plate connected with said bolt-element and slidably registered with the under surface of said upper wall of said shell, a catch-nosing connected with said bolt element and disposed within said shell, a depressible spring lock-plate arranged within said shell and provided with a receiving opening adapted to 100 embrace said catch-nosing, and an actuating spring for sliding said bolt carrying plate and its bolt-element in one direction when said catch-nosing is released from said spring lock-plate.

6. A bag-frame fastener comprising a chambered shell slotted in its upper wall, a bolt-carrying plate mounted to slide on the exterior side of the upper wall of said shell,

a bolt-element depending from said bolt carrying plate and extending downwardly through said shell, a keeper-plate connected with said bolt-element and slidably registered with the under surface of said upper wall of said shell, a catch-nosing connected with said bolt-element and disposed within said shell, a depressible spring lock-plate arranged within said shell and provided with 10 a receiving opening adapted to embrace said catch-nosing, a neck-piece connected with the free end of said spring lock-plate, said shell being provided in one end wall with an opening through which said neck-piece projects

exteriorly of said shell, a finger-piece on 15 the exterior end of said neck-piece for depressing said spring lock-plate, and an actuating spring for sliding said bolt carrying plate and its bolt-element in one direction when said catch-nosing is released from said 20 spring lock-plate.

In testimony, that I claim the invention set forth above I have hereunto set my hand this 4th day of January, 1915.

JULIUS HAMMESFAHR.
